UNITED STATES PATENT OFFICE.

ALBERT EDWARD JONES, OF FIUME, AUSTRIA-HUNGARY.

MEANS FOR ACTUATING SUBMERSION-RUDDERS FOR TORPEDOES.

No. 883,028.

Specification of Letters Patent. Patented March 24, 1908.

Application filed April 4, 1906. Serial No. 309,828.

To all whom it may concern:

Be it known that I, ALBERT EDWARD JONES, engineer, citizen of the United Kingdom of England, residing at Fiume, Empire 5 of Austria-Hungary, have invented certain new and useful Improvements in and Relating to Means for Actuating Submersion-Rudders for Torpedoes, of which the following is a specification, reference being had therein to 10 the accompanying drawing.

This invention has for its object an improvement in those devices which serve to maintain a traveling torpedo at a predetermined depth, and in which the movements 15 of the horizontal rudder are initiated on the one hand by a membrane submitted to hydrostatic pressure and to the pressure of a spring, and on the other hand by the oscillations of a pendulum.

20 The invention has mainly for its object that in place of the spring pressure maintaining equilibrium with the hydrostatic pressure, the rotary moment of a weighted arm positively connected with the membrane is utilized, this arm being so adjusted that in 25 the horizontal position of the axis of the torpedo, its moment is equivalent to the water pressure acting on the membrane at the normal depth of immersion.

30 As the rotary moment of the weighted arm increases or decreases with alterations in the horizontal position of the axis of the torpedo, the weighted pendulum also replaces the function of the submersion pendulum em- 35 ployed in the Whitehead torpedo.

In Figure 1 of the accompanying drawing a governor constructed in accordance with this invention is shown in vertical section built in the torpedo, together with the rear end of the 40 torpedo which contains the submersion rudder. Figs. 2 and 3 show a torpedo in position deviating from the horizontal line of travel, *i. e.* Fig. 2 in ascending and Fig. 3 in descending travel.

45 As shown by Fig. 1, the membrane *m* is arranged on the lower end of the hydrostatic chamber *a* and forms part of the cover *b* of a casing *c* extending into the chamber. The fixed part of the cover *b* carries two brackets *d* 50 and between them there is rotatably mounted an arm *f* provided with an adjustable weight *g*. Upon the shaft on which this arm rocks there is keyed an arm *h* which is connected with the center of the membrane by means of 55 a connecting rod *k*, this membrane *m* actuating in the known manner the servo or auxil-

iary motor *w* of the submersion rudder *z* by means of an appropriate rod *v*. The length of the connecting rod *k* and also that of the connecting member *v* is adjusted in such a 60 manner that the pendulum *f* assumes a slightly inclined position relatively to the vertical when the torpedo is in the horizontal position and the position of the membrane corresponds to the normal depth of immersion, that is to say to the horizontal position of the submersion rudder as shown in 65 Fig. 1.

The operation of the apparatus is as follows: With the axis of the torpedo in the 70 horizontal position and the torpedo at the normal depth of immersion the rotary moment of the weighted arm *f* counterbalances the hydrostatic pressure acting upon the membrane; the positive connection be- 75 tween the membrane and the steering apparatus being such that the rudder *z* is horizontal in this position of the torpedo, so that no upward or downward steering takes place. If the torpedo is situated at less 80 than the normal depth from the surface, the rotary moment of the pendulum will force the membrane outwards, by which means the rudder will be caused to rock down- 85 wards; if the depth of immersion however exceeds the normal, the membrane will be 90 pressed inwards, overcoming the counter pressure of the rotary moment of the pendulum and the rudder will be caused to rock upwards. Besides this function, which is 95 analogous to that of a spring acting upon the membrane, such as has already been em- 100 ployed, the weighted arm *f* also serves as the submersion pendulum, because its rotary moment increases or decreases with the incli- 105 nation of the longitudinal axis of the tor- 110 pedo, that is to say with an ascending direc- 115 tion of travel (see Fig. 2) it exceeds the normal magnitude and with a descending path (see Fig. 3) it is less than the normal magni- 120 tude. In the first case therefore an out- 125 ward pressure of the membrane exceeding the normal will take place the submersion rudder being thereby given a downward movement, while in the second case (Fig. 3) the membrane will be pressed inwards by 130 the water pressure and an upward move- 135 ment will be given to the horizontal rudder.

In the two typical positions of the torpedo represented in Figs. 2 and 3, the action of the 140 weighted arm will be directed to rendering the longitudinal axis of the torpedo hori-

zontal. Owing to the positive connection of the weighted arm *f*, which it is obvious will also act as a hydrostatic pendulum, with the membrane, the oscillation of the pendulum, caused by its inertia and occurring at the moment at which it reaches the water, is smaller and is more speedily checked than with those devices in which (as for example in the Whitehead submersion governors) the 10 depth or submersion pendulum acts quite independently of the membrane. Owing to this speedy checking of the oscillations of the weighted arm caused by the inertia, which checking results from the aforementioned 15 positive connection, the locking means by which in the arrangements hitherto adopted the submersion governor is arrested during the first period of the travel of the torpedo, may be dispensed with. This locking en- 20 tails as is well known, a number of incon-veniences, as its duration and the position given to the locked submersion rudder should differ with the different launching di-rections which direction is selected at the 25 moment of action, when it is not possible to make any adjustment.

As shown, the entire device is arranged in

a box *c* adapted to be placed in the hydrostatic chamber *a* and closed on all sides, so that the action of the membrane *m* will not be 30 influenced by any leakage occurring in the hydrostatic chamber *a* and the whole apparatus may be withdrawn from the torpedo without the necessity for dismounting other parts. 35

Having now particularly described and ascertained the nature of my said invention and in what manner the same is to be performed, I declare that what I claim is:

In depth or submersion governors a hydrostatic chamber, a closed box within said hydrostatic chamber, a membrane forming one side of the box and being exposed to the water pressure, a pendulum suspended in said box, and means for positively connecting the 40 membrane with the pendulum and holding the pendulum inclined to the vertical position.

In testimony whereof I hereunto affix my signature in presence of two witnesses.

ALBERT EDWARD JONES.
